UNITED STATES PATENT OFFICE.

JOSEPH G. CULLIGAN, OF NEW YORK, N. Y.

DESIGN FOR A GAME BOARD.

Application filed June 25, 1928. Serial No. 27,265. Term of patent 3½ years.

To all whom it may concern:

Be it known that I, JOSEPH G. CULLIGAN, a citizen of the United States, residing in the borough of Bronx, city, county, and State of New York, have invented a new, original, and ornamental Design for Game Board, of which the following is a specification, reference being had to the accompanying drawing, forming a part thereof. My new design has no appreciable thickness and may be placed upon any flat surface support on which the game could be played.

The figure is a top plan view of a game board, showing my new design.

I claim:

The ornamental design for a game board, as shown and described.

JOSEPH G. CULLIGAN.
